AUTOMATIC LIPSTICK HOLDER

Giles C. Fullmer, Bridgeport, Conn., assignor to
 The Bridgeport Metal Goods Manufacturing
 Company, Bridgeport, Conn., a corporation of
 Connecticut

Application January 13, 1933, Serial No. 651,462

14 Claims. (Cl. 206—56)

This invention relates to new and useful improvements in cosmetic holders and has particular relation to an automatic lipstick holder.

An object of the invention is to provide a holder for a cosmetic, such as a lipstick, eyebrow pencil or the like, and which holder includes a casing, a cover for the casing, a cosmetic carrier within the casing, and an operating means adapted on initial movement to open the cover and on further movement shift the carrier to project the cosmetic, and said operating means on reverse movement functioning to withdraw the cosmetic into the casing and return the cover to closed position.

A further object is to provide a cosmetic holder including a casing having a slot in a wall thereof, a cover for said casing, a member within the casing and normally closing the slot therein, a carrier within the casing, a finger piece including a portion extending through the slot in the casing, said finger piece adapted to be operated to shift said member to open the cover and the slot and thereafter on further movement shift the carrier, and said finger piece on reverse movement adapted to withdraw the carrier and member into the casing and return the member to its normal position closing the slot in the casing and return the cover to closed position.

Another object is to provide a cosmetic holder as stated and which is of simple construction and which may be operated with but one hand and which has a smooth easy operation.

An additional object is to provide a cosmetic holder having the characteristics described and which includes an improved cover construction whereby the open end of the casing of the holder is completely closed when the cover is in closed position and all foreign matter is effectively excluded.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a side elevational view of the complete holder in closed position, the position of the cover members when opened being indicated by dotted lines;

Fig. 2 is a top plan view of the holder closed;

Fig. 3 is a view similar to Fig. 1 but showing the

holder open and a lipstick partly projected for use;

Fig. 4 is a transverse sectional view taken substantially along the line 4—4 of Fig. 3;

Fig. 5 is a central longitudinal sectional view taken substantially along the line 5—5 of Fig. 3;

Fig. 6 is a view showing the upper portion or outer end portion of the holder, a portion of one side wall thereof being removed and the cover members being shown in section;

Fig. 7 is a side elevational view of the upper or outer end portion of one side wall of the casing;

Fig. 8 is a detail sectional view taken substantially along the line 8—8 of Fig. 3;

Fig. 9 is a front elevational view of a cam plate employed;

Fig. 10 is a top plan view of the cosmetic carrier;

Fig. 11 is a side elevational view of the carrier, a corner portion being broken away;

Fig. 12 is a view partly in elevation and partly in section showing one of the cover members removed; and

Fig. 13 is a transverse sectional view taken substantially along the line 13—13 of Fig. 12.

Referring in detail to the drawing, the improved holder as here disclosed includes an outer casing 15 of any desired size and configuration. As shown in the drawing, the casing is elongated and is transversely rectangular although it will be understood that the precise shape is not controlling. In one side wall 16 the casing is provided with a longitudinally extending slot 17 extending for a considerable portion of the length of the casing but stopping short of each of the ends of the latter. At its outer or upper end the casing is open while its inner or lower end is closed as by a wall 18.

The open end of the casing is normally closed by a cover means including a pair of complementary cover sections 19 and 20 each including an upper or top wall 21, side walls 22 and 23, and a rear wall or rear wall portion 24. These cover sections straddle the open end of the casing and are arranged in opposing relationship with their rear walls 24 disposed outwardly and with their side walls 22 and 23 arranged one at each side of the casing. Rivets or other suitable pivoting means 25 are passed through openings 26 in the side walls of the cover section and openings 27 in the side walls of the casing whereby to pivotally mount the cover sections on the casing.

The side walls of the cover sections have their lower opposed edge portions cut on an arc as

indicated at 28, the centers of the respective arc being represented by the pivots 25. When the cover sections are closed as shown in Fig. 1 the opposed edges of their top and side walls 5 are in abutting relation so as to effectively exclude powder, tobacco crumbs and the like, and their rear wall portions 24 are arranged above the upper or outer ends of the edge walls of the casing. It will, therefore, be seen that when the 10 cover sections are in closed position the open end of the casing is fully closed. On their pivots 25 the cover sections may be rocked into open positions in which they are disposed laterally of the receptacle as shown in Figs. 3 and 6 and it will 15 be noted that their arcuate edges 28 provide proper clearance.

Within the casing there is arranged a carrier 29 in the form of a small receptacle and this carrier is preferably of a size and shape to substantially fill the casing in a direction transversely of the casing. The carrier receives the lower end portion of a lipstick 30 and is adapted to be projected and retracted to project the lipstick for use and to retract or withdraw it into the casing 25 after use. A finger piece 31 in the form of a button is arranged at the outer side of the casing and has a stem portion 32 extending through the slot 17 in the casing and this stem portion at its inner end is connected to the carrier in any 30 suitable manner as by having its inner end portion 33 reduced and passed through the carrier and riveted over as clearly shown in Fig. 5. By engaging the finger piece 31 and shifting it along the slot 17 the carrier 29 may be shifted to projected and retracted positions. In one of its walls 35 the carrier has a portion 34 lanced and pressed therefrom to form a spring tongue which frictionally engages the inner surface of a wall of the casing whereby the carrier may be given a smooth 40 steady movement in the casing and whereby the carrier will be frictionally retained in the desired adjusted position within the casing.

Within the casing between the carrier 29 and the wall 16 of the casing there is arranged a cam 45 or operating plate 35 shown alone in Fig. 9. This plate is of less width and length than the wall 16 of the casing and is provided with a longitudinally extending slot 36 which at its lower end is offset laterally as at 37 whereby a shoulder 38 is provided. In its upper end portion the plate 35 is provided with a transversely extending slot 39 and inwardly of its upper end it is cut away to provide a straight surface or wall 40 communicating with an inclined slot 41 having an upper 50 wall 42 and a lower wall 43. In its opposite edge and adjacent its inner end the cam plate is cut away to provide a straight surface or wall 44 and an inclined or cam surface 45.

The stem or shank 32 of the button or finger 60 piece 31 extends through the slot 36 of the plate 35 and normally this plate is so arranged that its longitudinal slot 36 is located laterally of the longitudinal slot 17 in the casing wall whereby the plate 35 closes the latter slot. When the 65 parts are in this position the stem of the operating finger piece is in the off-set portion 37 of slot 36 and the carrier and lipstick are in retracted or withdrawn position. Adjacent or toward its upper or open end the casing has a 70 portion of its wall 16 pressed inwardly to provide a short projection or stud 46 and adjacent the lower end of the wall 16 a portion is pressed in to provide a stud or projection 47 and the projection 46 co-operates with the edge 40 and slot 41 and 75 the projection 47 co-operates with the edges 44

and 45, all on the plate 35, in a manner which will later be fully described.

Arcuate slots 48 and 49 are provided in the wall 16 of the casing adjacent the open end of the casing and each of these slots is struck on an arc the center of the radius of which is represented by the pivot openings 27 or by the pivots 25 in said openings. Each slot is closed at its ends as clearly shown in Figs. 6 and 7 and on its side wall 22 each cover section 19 and 20 carries an inwardly projecting pin 50 and the pin of cover section 19 passes through the arcuate slot 48 and into the transverse slot 39 in the upper end portion of the operating cam plate 35. Similarly the pin 50 of cover section 20 extends through the arcuate slot 49 and into the transverse slot 38.

In the operation of the device assuming the cover sections to be closed as shown in Figs. 1 and 2, the device may be held in one hand and the finger piece 31 engaged with the thumb of that hand. On an upward pressure being applied to the finger piece its stem or shank 32 engages the shoulder 38 of the plate 35 and shifts the plate upwardly. As the plate moves upwardly it carries the pins 50 on the side walls of the cover members upwardly shifting said pins through the arcuate slots 48 and 49 and rocking the cover members about their pivots 25 so that the cover members are carried to their open positions.

During this initial movement of the plate 35 its straight edges or walls 40 and 44 are in engagement with the studs or projections 46 and 47 respectively. After a short upward movement the said studs are engaged by the lower inclined wall 43 of slot 41 and by the inclined wall 45 and further upward pressure on the finger piece results in the cam plate being shifted laterally to bring its longitudinal slot 36 into registry with the longitudinal slot 17 in the side wall of the casing. When the parts reach this position the cover sections are open and the finger piece may be shifted upwardly shifting the carrier 29 upwardly to project the lipstick for use. As the 40 spring tongue 34 of the carrier is in engagement with the wall of the casing the carrier will be frictionally retained in adjusted position.

After the cosmetic has been used the finger piece 31 is drawn downwardly through the registering slots 36 and 17 drawing the carrier downwardly and retracting the lipstick into the casing. As the finger piece approaches the end of its inward or downward movement its stem engages the curved wall 51 of slot 36 and has a tendency to draw the plate 35 into the casing and to shift the plate laterally. This tendency to shift the plate laterally is assisted by engagement of the stud 46 with the upper inclined wall 42 of slot 41 and the lateral movement of the plate 60 carries its slot 36 out of registry with the slot 17 in the wall of the casing. The final movement of the cam plate is a straight longitudinal movement since its straight edge portions 40 and 44 are in the final movement of the plate in engagement with the studs 46 and 47 respectively.

During this final downward movement of the cam plate the cover sections 19 and 20 are swung about their pivots into their closed positions. This action takes place owing to the fact that 70 the pins 50 on the side walls 22 of the cover sections are engaged in the slot 39 in the upper end portion of the cam plate and as the cam plate is drawn downwardly said pins are also drawn downwardly rocking the cover sections about the 75

pivots 25 and into closed abutting relation. It will be apparent from a consideration of Figs. 1 and 3 that the side walls 22 of the cover sections serve to cover the arcuate slots 48 and 49 5 when the cover sections are in either closed or open positions.

The improved holder may be operated with but one hand while a mirror or the like is supported in the other hand and in the operation of 10 the device the cam plate 35 shifts the cover sections to open position before the lipstick reaches a position to engage said cover sections. On the return movement of the finger piece the lipstick is entirely within the casing before the cover 15 sections are rocked to closed positions. This action of retracting the lipstick into the casing and of closing the cover sections may be performed with but one hand since the finger piece may be operated by the thumb of the hand in which the 20 device is held.

From the foregoing description it will be seen that the improved device includes but a relatively few parts which may be stamped from sheet metal and easily and quickly assembled. While 25 the studs 46 and 47 are shown as pressed from a wall of the casing it will be understood that they may be in the form of separate pins suitably attached to or mounted on the casing. On the lower end of the casing there is shown a cap 52 30 which will give the same a finished appearance and which may be used as a support.

Having thus set forth the nature of my invention, what I claim is:

1. In a cosmetic holder, a casing having a 35 longitudinally extending slot in one of its walls, said casing having an open end, a cover normally closing said end of the casing, a cosmetic carrier within the casing and shiftable therein between a retracted position and a projected 40 position in which latter it is disposed to expose the cosmetic at the open end of the casing, a plate within the casing and adapted to be shifted between a projected and a retracted position, said plate having a longitudinally extending slot 45 therein, said slot including an offset portion forming a shoulder, a finger piece extending through the slot in the casing and the slot in the plate and engaging said carrier, said finger piece normally disposed in the offset portion of the 50 slot in the plate, said finger piece movable in said slots to shift the carrier and plate to projected and retracted positions, said finger piece adapted in the initial portion of said movement to engage the shoulder on the plate and 55 shift the plate to project an end of the same through the open end of the casing to have the plate engage and open said cover before the cosmetic in the carrier reaches the end of the casing, said plate having a straight surface and 60 an inclined surface adjacent each of its ends, and means carried by the casing and operating against said surfaces whereby the plate has an initial substantially straight longitudinal movement to open the cover and then has a lateral 65 movement to carry its slot into registry with the slot in the casing.

2. In a cosmetic holder, a casing having an open end and a longitudinally extending slot in a side wall, a pair of cover members pivoted on 70 said casing adjacent its open end and normally closing the open end of the casing, a cosmetic carrier within the casing and shiftable to and from a position to expose a cosmetic beyond the end of the casing, a finger piece extending through the slot in the casing and connected

with the carrier to shift the same, an operating plate within the casing, said casing having a pair of slots in its side wall adjacent its upper end, said plate having a transversely extending slot in its upper end portion, a projection on 5 each of said cover members radially of its pivot, said projections extending through the respective slots in the casing and into the slot in the plate, said finger piece adapted on its initial movement in one direction to shift said plate 10 and through said projections rock said cover members about their pivots to an open position, and said finger piece adapted as it completes its movement in the opposite direction to shift said plate and through said projections rock said 15 cover members about their pivots to closed position.

3. In a cosmetic holder, a casing having an open end and a longitudinally extending slot in a side wall, a pair of cover members, each of said 20 cover members including a top, spaced side walls and a rear wall, means pivoting the side walls of said cover members to the casing adjacent its open end, said cover members normally closing the open end of the casing, a cosmetic carrier 25 within the casing and shiftable to and from a position to expose a cosmetic beyond the end of the casing, a finger piece extending through the slot in the casing and connected with the carrier to shift the same, an operating plate within the 30 casing, said casing having a pair of slots in its side wall adjacent its open end, said plate having a transversely extending slot in its outer end portion, a projection on one side wall of each of said cover members radially of its pivot, 35 said projections extending through the respective slots in the casing and into the slot in the plate, said finger piece adapted on its initial movement in one direction to shift said plate and through said projections rock said cover 40 members about their pivots to open position, said finger piece adapted as it completes its movement in the opposite direction to shift said plate and through said projections rock said cover 45 members about their pivots to closed position, said side walls of the cover members closing the slots in the open end portion of the casing, and said rear walls of the cover member closing the spaces between the tops of the cover members and the upper side edges of the casing when the 50 cover members are in closed position.

4. In a cosmetic holder, a casing having an open end and a longitudinally extending slot in a side wall, a pair of cover members, each of said 55 cover members including a top and spaced side walls, means pivoting the side walls of said cover members to the casing adjacent its open end, said cover members normally closing the open end of the casing, a cosmetic carrier within the casing and shiftable to and from a position to expose a cosmetic beyond the end of the casing, a finger piece extending through the slot in the casing and connected with the carrier to shift the same, an operating plate within the 60 casing, said casing having a pair of slots in its side wall adjacent its open end, said plate having a transversely extending slot in its outer end portion, a projection on one side wall of each of said cover members radially of its pivot, said 65 projections extending through the respective slots in the casing and into the slot in the plate, said finger piece adapted on its initial movement in one direction to shift said plate and through said projections rock said cover members about their pivots to open position, said finger piece 70

75

adapted as it completes its movement in the opposite direction to shift said plate and through said projections rock said cover members about their pivots to closed position, and said side walls 5 of the cover members closing the slots in the open end portion of the casing.

5. In a cosmetic holder, a casing having an open end and a longitudinally extending slot in a side wall, a cover member, said cover member 10 including a top and a side wall, means pivoting the side wall of the cover member to the casing adjacent the open end of the latter, said cover member normally having its top wall disposed over the open end of the casing, a cosmetic carrier 15 within the casing and shiftable to and from a position to expose a cosmetic beyond the end of the casing, a finger piece extending through the slot in the casing and connected with the carrier to shift the same, an operating plate 20 within the casing, said casing having a slot in its side wall adjacent its open end, said plate having a transversely extending slot in its outer end portion, a projection on the side wall of the cover member radially of its pivot, said projection ex- 25 tending through the slot adjacent the open end of the casing and into the slot in the plate, said finger piece adapted on its initial movement in one direction to shift said plate and through said projection rock said cover member about its 30 pivot to open position, said finger piece adapted as it completes its movement in the opposite direction to shift said plate and through said projection rock said cover member about its pivot to closed position, and said side wall of the cover 35 member closing the slot in the open end portion of the casing when said cover member is in normal position.

6. In a cosmetic holder, a casing having an open end and a longitudinally extending slot in a side wall, a cover member, said cover member 40 including a top and a side wall, means pivoting the side wall of the cover member to the casing adjacent the open end of the latter, said cover member normally having its top wall disposed over the open end of the casing, a cosmetic carrier 45 within the casing and shiftable to and from a position to expose a cosmetic beyond the end of the casing, a finger piece extending through the slot in the casing and connected with the carrier to shift the same, an operating plate within the casing, said casing having a slot in its side wall adjacent its open end, said plate having a transversely extending slot in its outer end portion, a projection on the side wall of the cover 50 member radially of its pivot, said projection extending through the slot adjacent the open end of the casing and into the slot in the plate, said finger piece adapted on its initial movement in one direction to shift said plate and through said projection rock said cover member about its pivot to open position, said finger piece adapted as it completes its movement in the opposite direction to shift said plate and through said projection rock said cover member about its pivot to closed 55 position, said side wall of the cover member closing the slot in the open end portion of the casing when said cover member is in normal position, and means whereby as said cover member is shifted to and from closed position said 60 operating plate is shifted to and from a position closing said longitudinally extending slot in the side wall of the casing.

7. A container of the class described comprising a casing having a longitudinal slot, a pivoted 75 closure for said casing, a closure operator longi-

tudinally movable in said casing, an arcuate slot in said casing concentric with the closure pivot, a pin projecting from the closure through said arcuate slot and connected with the end of said closure operator, a carrier longitudinally slidible in said casing, and means engaging said carrier and extending through said longitudinal slot for actuating said carrier and said closure operator. 5

8. In a cosmetic holder, a casing having an open end, said casing having a longitudinally 10 extending slot in a side wall, cover means normally closing the open end of the casing, a cosmetic carrier within the casing and shiftable from a normal retracted position to a projected position to expose the cosmetic at the open end 15 of the casing, a movable member mounted for both longitudinal and lateral movements within the casing and having a longitudinal slot, a finger piece extending through and operable in the slots in the casing and movable member and connected with the carrier, means on the movable member arranged to be engaged by said finger piece on initial movement in one direction to shift said member longitudinally to open the cover means, said finger piece on further movement in said direction adapted to shift the carrier to projected position to expose the cosmetic carried thereby, a connection between said member and cover means, means on the movable member arranged to be engaged by said finger 20 piece as it completes its return movement to shift said member to have the latter through said connection return said cover means to closed position, and means operating on longitudinal movements of said member to shift the member laterally to carry its slot to and from alignment with the slot in the casing. 25

9. In a cosmetic holder, a casing having an open end, said casing having a slot in a side wall, cover means normally closing the open end of the casing, said cover means comprising a pair 40 of cover sections each pivoted on the casing adjacent its open end and swingable in opposite directions from a closed position over the end of the casing to an open position where one is disposed at each side of the casing inwardly of the open end thereof, a cosmetic carrier within the casing and shiftable from a normal retracted position to a projected position to expose the cosmetic at the open end of the casing, 45 a movable member mounted for both longitudinal and lateral movements within the casing and having a longitudinal slot, a finger piece extending through and operable in the slots in the casing and movable member and connected with the carrier, means on the movable member engageable by said finger piece on initial movement in one direction to shift said member longitudinally to open the cover means, said finger piece on further movement in said direction adapted to shift the carrier to projected position to expose the cosmetic carrier thereby, means on the movable member engageable by said finger piece as it completes its return movement to shift said member to return said cover means to closed position, 55 and means operable by said longitudinal movements of said member to shift the member laterally to bring its slot to and from alignment with the slot in the casing. 60

10. In a cosmetic holder, a casing having an open end and a longitudinally extending slot in one wall, a pair of cover members pivoted on said casing adjacent its open end and normally closing the open end of the casing, a cosmetic carrier within the casing and shiftable to and 75

from a position to expose a cosmetic beyond the end of the casing, an operating member mounted for both longitudinal and lateral movements within the casing and having a longitudinal slot 5 provided with an offset, a finger piece extending through the slots in the casing and the operating member and connected with the carrier to shift the same, said finger piece on its initial movement in one direction engaging a wall of said 10 offset to shift said member and rock said cover members about their pivots to an open position, a connection between said plate and cover members, said finger piece adapted as it completes its movement in the opposite direction to engage 15 a wall of said offset to shift said member and through said connection rock said cover members about their pivots to closed position, and means operable by said movements of the member to shift it laterally to bring its slot to and 20 from alignment with the slot in the casing.

11. In a cosmetic holder, a casing having an open end and a longitudinally extending slot in a side wall, a cover member, said cover member including a top and a side wall, means pivoting 25 the side wall of the cover member to the casing adjacent the open end of the latter, said cover member normally having its top wall disposed over the open end of the casing, an operating member mounted for both longitudinal and lateral movements within the casing and having a longitudinal slot provided with an offset, a pin 30 and slot connection between said operating plate and the side wall of the cover member, a cosmetic carrier within the casing and shiftable to and 35 from a position to expose a cosmetic beyond the end of the casing, a finger piece extending through the slots in the casing and operating member and connected with the carrier to shift the same, said finger piece adapted on its initial 40 movement in one direction to engage a wall of the offset to shift said operating member and through said pin and slot connection rock said cover member about its pivot to open position, said finger piece adapted as it completes its 45 movement in the opposite direction to engage the opposite wall of said offset to shift said operating member and through said pin and slot connection rock said cover member about its pivot to closed position, and means operating on said movements 50 of the operating member to shift said member laterally to bring its slot to and from alignment with the slot in the casing.

12. In a cosmetic holder, a casing having an open end, said casing having a longitudinally 55 extending slot in a side wall, cover means normally closing the open end of the casing, a cosmetic carrier within the casing and shiftable from a normal retracted position to a projected position to expose the cosmetic at the open end 60 of the casing, a movable member mounted for both longitudinal and lateral movements within the casing, a finger piece extending through and operable in the slot in the casing and connected with the carrier, means on the movable member 65 arranged to be engaged by said finger piece on initial movement in one direction to shift said member to open the cover means, said finger piece on further movement in said direction adapted to shift the carrier to projected position to expose 70 the cosmetic carried thereby, means on said mov-

able member arranged to be engaged by said finger piece as it completes its return movement to shift said member to return said cover means to closed position, and means whereby as said cover means is shifted to and from closed position said 5 movable member is shifted laterally to and from a position closing said longitudinally extending slot in the side wall of the casing.

13. In a cosmetic holder, a casing having an open end, said casing having a longitudinally extending slot in a side wall, cover means normally closing the open end of the casing, a cosmetic carrier within the casing and shiftable from a normal retracted position to a projected position to expose the cosmetic at the open end of the 10 casing, a movable member mounted for both longitudinal and lateral movement within the casing, a finger piece extending through and operable in the slot in the casing and connected with the carrier, means on the movable member arranged to be engaged by said finger piece on initial movement in one direction to shift said member to open the cover means, said finger piece on further movement in said direction adapted to shift the carrier to projected position to expose the cosmetic carried thereby, a connection between said member and cover means, means on the movable member arranged to be engaged by said finger piece as it completes its return movement to shift said member to have the latter through said connection return 15 said cover means to closed position, and means whereby as said cover means is shifted to and from closed position said movable member is shifted laterally to and from a position closing said longitudinally extending slot in the side wall of the casing.

14. In a cosmetic holder, a casing having an open end and a longitudinally extending slot in a side wall, a cover member, said cover member including a top and a side wall, means pivoting the side wall of the cover member to the casing adjacent the open end of the latter, said cover member normally having its top wall disposed over the open end of the casing, a cosmetic carrier within the casing and shiftable to and from a position to expose a cosmetic beyond the end of the casing, a finger piece extending through the slot in the casing and connected with the carrier to shift the same, a cover operating member 40 within the casing and mounted for both longitudinal and lateral movement, a pin and slot connection between said operating member and the side wall of the cover member, means connecting said finger piece to the operating member adapted on its initial movement in one direction to shift said member longitudinally and through said pin and slot connection rock said cover member about its pivot to open position, means on said member in position to be engaged 45 by said finger piece as it completes its movement in the opposite direction to shift said plate and through said pin and slot connection rock said cover member about its pivot to closed position, and means whereby as said cover member is shifted to and from closed position said operating member is shifted laterally to and from a position closing said longitudinally extending slot in the side wall of the casing.

GILES C. FULLMER. 70
